UNITED STATES PATENT OFFICE.

JULIUS HIRSH, OF PHILADELPHIA, PENNSYLVANIA, ASSIGNOR TO ELK
KNITTING MILLS COMPANY, OF SAME PLACE.

DESIGN FOR AN UNDERGARMENT.

SPECIFICATION forming part of Design No. 34,853, dated July 23, 1901.

Application filed May 15, 1901. Serial No. 60,407. Term of patent 7 years.

To all whom it may concern:

Be it known that I, JULIUS HIRSH, a citizen
of the United States, residing in Philadelphia,
Pennsylvania, have invented or produced a
new and original Design for an Undergar-
ment, of which the following is a specification.

My design for an undergarment is fully
shown in the accompanying drawing.

The essential feature of the design consists
10 of an undergarment having overlying breast-
flaps, each extending from the arm portion to
the center of the garment, the lower edges of
said overlying breast-flaps having ornamental
15 borders and each of said lower edges present-
ing a reverse curve, the inner curves of each
flap meeting at the center and forming a con-
tinuous convex curve at that point.

1 represents the body of the garment, 2
the sleeves, and 3 the breast-flaps, the lower
20 edge of each of the latter presenting a re-

verse curve—that is to say, an outer concave
curve 4, beginning at the sleeve, and an in-
ner convex curve 5, extending to the inner
edge of the flap, so that said convex curves
meet where the flaps join or overlap at the 25
center.

The neck-opening of the garment and the
two breast-flaps have ornamental edging.

Having thus described my invention, I
claim and desire to secure by Letters Patent— 30

The design for an undergarment substan-
tially as described and as shown in the ac-
companying drawing.

In testimony whereof I have signed my
name to this specification in the presence of 35
two subscribing witnesses.

JULIUS HIRSH.
